UNITED STATES PATENT OFFICE.

FRED. A. LANE, OF NEW HAVEN, CONNECTICUT.

TIME AND ALARM CLOCK MOVEMENT.

SPECIFICATION forming part of Letters Patent No. 268,911, dated December 12, 1882.

Application filed July 17, 1882. (No model.)

To all whom it may concern:

Be it known that I, FRED. A. LANE, of New Haven, in the county of New Haven and State of Connecticut, have invented a new Improvement in Clock-Movements; and I do hereby declare the following, when taken in connection with the accompanying drawings and the letters of reference marked thereon, to be a full, clear, and exact description of the same, and which said drawings constitute part of this specification, and represent, in—

Figure 1, a front view; Fig. 2, a side view, enlarged; Fig. 3, an opposite side view, enlarged; Fig. 4, a top view, enlarged, portions of these views broken away to show sections.

This invention relates to an improvement in clock-movements, with special reference to the movement, for which Letters Patent No. 237,028 were granted to me, dated January 25, 1881. In that patent the movement was adapted to a pendulum-escape. The object of my present invention is to adapt substantially that movement to a "marine" escapement, also to combine therewith an alarm; and the invention consists in a frame consisting of a front plate, an intermediate plate, and a rear plate, the actuating mechanism arranged between the rear and intermediate plates communicating its power to the train arranged between the front and intermediate plates, said train communicating with the escapement-wheel, the lever and balance acting in connection therewith also arranged between the front and intermediate plates, combined with an alarm-movement arranged between the rear and intermediate plates on bearings independent of the bearings or shafts of the time-movement, as more fully hereinafter described.

As in my previous patent, I employ three plates to form the frame of the movement. A is the rear plate, B the front plate, and C the intermediate plate; but unlike my previous patent, in which the rear and intermediate plates extended down below the front plate—that is, to about twice the length of the front plate, with the actuating mechanism arranged in the lower part of the space between the rear and intermediate plates—I make the plates of equal size, the three plates connected together by pillars D at the corners.

E is the main wheel, arranged loose upon the

shaft a, the said shaft taking its bearing in the rear and intermediate plates and extending through the rear plate to receive the winding-key F. The mainspring is attached by one end to the frame, and the other to the shaft a. On the shaft a is a ratchet, b, and on the main wheel E a spring-pawl, d, engaging the teeth of the said ratchet, so that by turning the key F the spring will be wound in the usual manner of winding clocks.

G is the center-shaft, which extends through the three plates from front to rear, made angular on its rear end, as at e, to receive a key for setting the pointers, the opposite or front end fitted to receive the pointers in the usual manner. The main wheel E works into a pinion, H, on the center shaft, G, between the rear and intermediate plates, and through which power is communicated to the train, the train being arranged between the front and intermediate plates to communicate the power to the escapement-wheel I, into which the lever K plays, vibratory movement of the lever being imparted by the balance-wheel L, the balance-wheel escapement, and the wheels of the train taking their bearing in the front and intermediate plates. By this construction I adapt the movement to a marine escapement and contract the movement into a very small compass.

To apply to this movement an alarm without adding to the space occupied by the movement I arrange a shaft, f, through from the front to the rear plate, and at the front attach a gear, g, of equal size, and so as to work into the gear h, which receives its movement from the pinion on the center-shaft and from the pinion i, from which the hour-hand wheel is driven, the minute-hand being fixed directly to the center-shaft, which makes one revolution each hour. The pinion l on the shaft F works into a gear, m, arranged loose upon a shaft, n, between the rear and intermediate plates, the proportion of the pinion l to the wheel m being such that the wheel m will revolve with the hour-pointer—that is, one revolution each twelve hours.

On the hub of the wheel m is a cam, o, and on the shaft n is a radial stud, p, which stands against the cam-shaped end of the hub. The shaft n is provided with any suitable frictional device (here represented as a spring, r,) which

will create friction between the shaft and the frame, so that while the shaft may be turned to any desired position when in that position the friction will hold the shaft, so that the 5 wheel *m* may revolve thereon without imparting rotation to the shaft. This shaft *n* is the setting-shaft. It is turned to change the position of the stud *p* and bring it into the position that the shoulder of the cam may escape 10 from the stud at the time at which it is desired the alarm should be sounded. A spring-lever, *s*, bears upon the rear of the wheel, tending to force it toward the stud, and so that as the wheel *m* revolves the face of the cam will 15 work against the stud, gradually throwing the wheel *m* rearward until it arrives at the shoulder. Then the spring-lever will force the wheel *m* forward, which permits a corresponding movement of the end of the lever. The pinion *l* is of sufficient length to permit this axial 20 movement of the wheel *m*.

Between the rear and intermediate plates on a shaft, *M*, the main wheel *N* of the alarm is arranged with a spring, *R*, in connection 25 with the frame and the shaft, the shaft extending to the rear, as at *T*, so that the spring may be wound, the usual pawl and ratchet being provided to connect the main wheel with the shaft. The main wheel works into a pinion, *t*, 30 on a shaft, *u*. The said shaft also takes its bearing in the rear and intermediate plates and carries the escapement-wheel *w*, which works into the verge *x* of the alarm-hammer, in the usual manner of working alarm-escapements. The hammer-shaft also takes its bearings in the rear and intermediate plates. The 35 lever *s* extends toward the hammer-shaft and carries a stud, *2*, which, when the wheel *m* is thrown back, takes the stud *2* beneath an arm, *3*, 40 on the hammer-shaft, which holds the hammer and prevents the verge escaping from the wheel *w*; but so soon as the wheel *m* escapes from the stud *p*, so as to be thrown forward, as before described, the lever *s* moves forward to take 45 the stud *2* from engagement with the arm *3* of the hammer, leaving the hammer free for vi

bration until the alarm-spring has run down. Then, as the time part continues its movement it gradually turns the wheel *m* until it is forced back by the action of the cam on its hub 50 against the stud *p*, which movement will again bring the spring-lever *s* into engagement with the hammer. Then the alarm may be rewound and sounded, as before, unless it be desired to change the time of the alarm. If this be the 55 case the shaft *n* will be turned, as before described, to bring the stud *p* into position corresponding to the time when it is desired the alarm shall be sounded. By this construction the alarm-movement is brought between the 60 rear and intermediate plates above the main wheel of the time-movement and into a space not otherwise occupied, hence adds nothing to the size of the movement, and this is done without employing any of the shafts of the time-movement as bearings for the alarm-movement, which has heretofore been necessary in order 65 to bring the alarm-movement into the space occupied by the time-movement.

From the foregoing it will be understood 70 that I do not claim broadly a three-plate clock-movement having the main wheel arranged between the rear and intermediate plates to communicate the power of the spring to the train between the intermediate and front plates; 75 but

What I do claim is—

In a clock-movement consisting of the rear plate, *A*, the front plate, *B*, the intermediate plate *C*, the actuating mechanism arranged 80 between the rear and intermediate plates, communicating with the train between the front and intermediate plates, and an alarm-movement arranged between the rear and intermediate plates on bearings independent of the bearings or shafts of the time-movement, substantially as described. 85

FRED. A. LANE.
